United States Patent Office

Des. 203,919
Patented Feb. 22, 1966

203,919

HAIR DRYER

Thomas H. Hayes, Chicago, Ill., assignor to Sunbeam
Corporation, Chicago, Ill., a corporation of Illinois

Filed July 13, 1965, Ser. No. 86,134

Term of patent 14 years

(Cl. D86—10)

Fig. 1.

Fig. 2.

FIG. 1 is a front perspective view of a hair dryer showing my new design;

FIG. 2 is a top plan view thereof;

FIG. 3 is a rear elevational view thereof; and

FIG. 4 is an end view thereof.

I claim:

The ornamental design for a hair dryer, as shown.
